US0D1087174S

(12) **United States Design Patent** (10) **Patent No.:** **US D1,087,174 S**
(45) **Date of Patent:** **** Aug. 5, 2025**

(54) **HYDRAULIC EXCAVATOR**

(71) Applicant: **Hitachi Construction Machinery Tierra Co., Ltd.**, Koka (JP)

(72) Inventors: **Yuuki Umizaki**, Koka (JP); **Kohei Maeda**, Koka (JP); **Makoto Motozu**, Koka (JP); **Katsumi Usami**, Tokyo (JP); **Yusuke Daimon**, Tokyo (JP); **Masaru Oda**, Tokyo (JP); **Atsushi Ninomiya**, Tokyo (JP)

(73) Assignee: **Hitachi Construction Machinery Tierra Co., Ltd.**, Koka (JP)

(**) Term: **15 Years**

(21) Appl. No.: **29/881,284**

(22) Filed: **Dec. 29, 2022**

(30) **Foreign Application Priority Data**

Jun. 30, 2022 (JP) ..... 2022-014097 D

(57) **CLAIM**

The ornamental design for a hydraulic excavator as shown and described.

DESCRIPTION

FIG. 1 is a top, right perspective view of a hydraulic excavator showing the claimed design;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof; and,

FIG. 8 is a top, left perspective view thereof.

The dashed broken lines in the Figs. show portions of the hydraulic excavator that form no part of the claimed design.

1 Claim, 8 Drawing Sheets
